UNITED STATES PATENT OFFICE

2,631,450

PRESTRESSED REINFORCED CONCRETE
FLOOR BEAMJean Celestin Hippolyte Lachaise,
Vitry-sur-Seine, FranceApplication October 13, 1945, Serial No. 622,128
In France July 6, 1943Section 1, Public Law 690, August 8, 1946
Patent expires July 6, 1963

3 Claims. (Cl. 72—61)

1

The object of the present invention is a prestressed reinforced concrete floor, which is particularly characterized by very great lightness and strength. Another object of this invention is a beam designed for the manufacture of said floor, which can easily be manufactured by quantity production and is consequently inexpensive; a number of such beams may be assembled in a very simple manner to constitute a floor of any size. This invention is also concerned with processes for the manufacture of said floor and beams.

The beam according to this invention is made of concrete or like material, and is given substantially on the whole, an I cross-section, and two metal rods at least, set in tension, are disposed near its end faces, means being provided to impart to the beam the compression stresses from the said rods. The substantially if not formally I cross-sections of the beam can be obtained by making up a twin-beam; the two elementary beams constituting the said twin-beam are each given substantially a U cross-section and are fastened together in a way to impart to the beam proper the compression stresses from the above mentioned rods.

According to a first embodiment of the invention, the beam comprises two elementary beams of U cross-section which are disposed so that their bottoms are opposite each other; two metal rods, under tension, are placed between said bottoms, preferably one near the upper and the other near the lower wings of the elementary beams. Said wings compose the upper and lower faces of the floor. Advantageously, the bottoms of the elementary beams are spaced apart, the distance being sufficient to enable pouring concrete between them and the metal rods, whatever the diameter of the latter is.

In all embodiments, at the end of each beam is disposed a counter-plate, such as a metal plate, on which the metallic rods are anchored, said plate distributing the stresses onto the whole mass of concrete.

In all the embodiments above described, use is made of elementary beams the wings of which are not particularly thick, and, preferably, said thickness decreases from the bottom of the beam up to its longitudinal edge. It is consequently advantageous to provide, at convenient intervals, cross-partitions which are moulded together with the beam. They act as sustainers for the wings which, otherwise, would be too sensitive to collisions, and simultaneously as stiffeners to avoid warping of the beam. In or-

2

der to facilitate the subsequent joining of the beams, which are disposed side by side to form the floor, each beam may be formed so that one of the cross-partitions is off-set with respect to the longitudinal edge of the wing, the offset or outwardly projecting partition portion fitting into the adjacent beam. In this manner, the adjacent beams fit one in the other and constitute a whole.

10 Other characteristics of the present invention will appear from the following detailed description of some embodiments thereof together with the accompanying drawings given merely by way of non-limitative example, and in which:

15 Fig. 1 is a partial cross-section of a floor according to the invention;

Fig. 2 is an isometric view of a beam built up by joining two elementary beams;

20 Fig. 3 is a view similar to Fig. 2 but showing a modified form of end member.

Referring now to the drawings, in which like reference numerals denote similar elements, a section of a typical floor constructed from beams which form the invention is illustrated, the floor being constituted by a plurality of concrete beams, such as those indicated by reference numerals 1 and 2, disposed side by side. Preferably the upper wings, such as wings 3 and 4, and wings 5 and 6, of adjacent beams are in

25 contact, as may be accomplished with the construction shown in Fig. 3, and so likewise should be together the lower wings 4a, 3a, and 5a, 6a. Each beam such as 1 and 2 is constituted, in this embodiment, by two elementary beams 7 and 8, which are disposed opposite each other, their wings being divergent and approximately horizontal. Said elementary beams are of U cross-section; their bottoms 9 and 10 are uniformly

35 distant one from the other, said distance being such that, regardless of the diameter of rods 11—12, there remains, between the latter and the bottoms 9, 10 a space which is sufficient to allow for the easy introduction of the filling concrete 13.

40 As shown on Fig. 2, cross-partitions or plates 14 are spaced from each other in the elementary beam so as to stiffen the same and sustain the wings 5 and 5a. Figs. 1 and 2 show a partition plate 14 projecting outwardly beyond the longitudinal edges of the wings of one beam, and the partition plate in the other beam which aligns with this plate is accordingly shortened. As shown in Figure 1, the partition 14 protrudes from the longitudinal edge of the elementary beam 5 and the opposite partition 14 has its

edge recessed with respect to the longitudinal edge of the elementary beam 6. By way of example, five cross-partitions may be provided for each elementary beam. At their end, the elementary beams 7 and 8, constituting the beam proper, are capped by a counterplate 15 which supports the rods 11 and 12 and distributes on the elementary beams 7, 8 the compression stresses transmitted by said rods. As shown in Fig. 2, counterplate 15 is in the nature of a box enclosing the end of the elementary beam; the wings 16, of the counterplate respectively overlying and underlying the upper and lower wings 3, 5 and 3a, 5a of the beam ends and the wings 20, of the counterplate completing the encasement of the beam ends. In this embodiment, counterplate 15 distributes the compression stresses transmitted by rods 11 and 12 over the entire end surfaces of the beams 7, 8 and, in addition, the counterplate wings 16, 16' and 20, predetermined that the beams will be precisely positioned and spaced with respect to one another.

The ends of rods 11, 12 are, preferably, threaded and the rods are placed under tension by screwing nuts 17 on the ends. It is however understood that use may be made of any desired process for anchoring or placing the rods 11, 12 under tension.

The embodiment shown in Fig. 3 is identical to the one shown in Fig. 2 except in that counterplate 15a is U-shaped in cross section, and has only the arms 16a which bracket the ends of beams 7 and 8.

The beams are in each instance provided with the cross-partitions 14 above described, whatever the embodiment may be.

The construction of a floor by using the above described beams is effected by placing side by side the desired number of these beams and then spreading a coating material over the surface of the floor so obtained. The cross-partitions 14 secure the joining of the beams by reason of their being fitted between the wings.

There may be manufactured in a plant, either the elementary beams which are afterwards assembled on the ground and the rods which are placed under tension before pouring concrete in the free intervals, or the beam proper, the concrete being poured only when the floor is built up. These operations may also be performed on the ground.

It will be understood that the concrete which is poured about the rods is particularly intended to protect these rods against corrosion. Instead of concrete a suitable filling material may be used, or the rods may be coated with an anti-corrosion product. It is also possible to place the rods under tension after the setting of the beams side by side and dispose a single counterplate on each side of the floor for all of the beams.

What I claim is:

1. A beam which comprises a composite fabrication including, in combination, two elongate continuous beam elements disposed parallel to and closely spaced from one another, clamping means disposed at each end of said elements and having substantially a U cross-section, the respective ends of the two elements being disposed within the clamping means of substantially U-shaped cross section, the corresponding extremities of the two elements abutting the

web of one of said clamping means and the flanges of said clamping means overlying and snugly engaging the surfaces of the two corresponding element ends, and metal rods set in tension and anchored on said clamping means so as to force them one towards the other, said metal rods being disposed between said two elements.

2. A beam which comprises a composite fabrication including, in combination, two elementary beams of substantially U-cross-section disposed back to back with their backs closely spaced from one another, said beams each having divergent wings, cross-partitions provided in each elementary beam between its wings, one of said cross-partitions being off-set inwardly with respect to the free edges of the wings and the following cross partition projecting the same amount outwardly with respect to the free edge of the wings, a substantially rectangular box-shaped clamping means having an open side therein disposed at each extremity of the composite beam with the corresponding ends of the two elementary beams extending through the said open side and disposed within the box-shaped clamping means and abutting the base thereof, the walls of the clamping means surrounding and snugly engaging the surfaces of the two corresponding elementary beam ends, and metal rods set in tension and anchored on said clamping means so as to force them one towards the other, said metal rods being disposed between said two elementary beams.

3. A preformed beam designed to be delivered as a unit to the place where it is to be used, said beam comprising two elementary U beams of elongate unitary form with the bottoms of the U's arranged opposite to and spaced from each other, a box-like end member for each end of the elementary beams, each end member enclosing the adjacent ends of both beams and predetermined the positioning of same, and metal rods disposed in the space between the elementary beams, anchored to said end members and tensioned to force the end members toward each other.
